United States Patent Office

Des. 196,795
Patented Nov. 5, 1963

196,795

HOSE SUPPORTER OR SIMILAR ARTICLE

Richard K. Sutz, Lausanne, Switzerland (% Everett A. Johnson, 15 S. Prospect Ave., Park Ridge, Ill.)

Filed Sept. 4, 1962, Ser. No. 71,566

Term of patent 14 years

(Cl. D17—8)

FIG. 2.

FIG. 1.

FIGURE 1 is a front perspective view of a hose supporter or similar article showing my new design; and

FIGURE 2 is a rear perspective view thereof with the button members shown in closed position.

The dominant portion of the design is shown in full lines.

I claim:

The ornamental design for a hose supporter or similar article, as shown and described.
